UNITED STATES PATENT OFFICE

159,351

BOOT SCRAPER

Nina I. Law, Colorado Springs, Colo.

Application May 5, 1949, Serial No. 2,449

Term of patent 3½ years

(Cl. D9—6)

To all whom it may concern:

Be it known that I, Nina I. Law, a citizen of the United States, residing at Colorado Springs, in the county of El Paso and State of Colorado, have invented a new, original, and ornamental Design for a Boot Scraper, of which the following is a specification, reference being had to the accompanying drawing, forming a part hereof.

In the accompanying drawing:

Fig. 1 is a top plan view of a boot scraper showing my new design;

Fig. 2 is a front elevation view thereof; and
Fig. 3 is a left hand side view of Fig. 2.

I claim:

The ornamental design for a boot scraper, substantially as shown.

NINA I. LAW.
